UNITED STATES PATENT OFFICE

119,430

DESIGN FOR A COMBINED FLOWER BLOCK AND DISPLAY STAND THEREFOR

Horace A. Fuld, New York, N. Y.

Application November 9, 1939, Serial No. 88,130

Term of patent 7 years

To all whom it may concern:

Be it known that I, Horace A. Fuld, a citizen of the United States of America, residing in New York city, in the Borough of Manhattan, county and State of New York, have invented a new, original, and ornamental Design for a Combined Flower Block and Display Stand Therefor, of which the following is a specification, reference being had to the accompanying drawing, forming part thereof, wherein, bined flower block and display stand therefor showing my new design.

I claim:

The ornamental design for a combined flower block and display stand therefor, substantially as shown.

HORACE A. FULD.
